FIRE HYDRANT

Jay O. Garrett, Provo, Utah, and Lloyd M. Gustaveson,
Santa Clara, Calif., assignors to Pacific States Cast
Iron Pipe Company, Division of McWane Cast Iron
Company, a corporation of Delaware

Filed May 29, 1967, Ser. No. 7,289

Term of patent 14 years

(Cl. D23—12)

Fig. 1

Fig. 2

Fig. 3

Fig. 4

FIG. 1 is a front elevational view of a fire hydrant showing our new design;

FIG. 2 is a side elevational view thereof;

FIG. 3 is a rear elevational view thereof; and

The bottom surface of the bottom flange on the fire hydrant is plain and unornamental.

We claim:

The ornamental design for a fire hydrant, as shown and described.
